(57) **CLAIM**

The ornamental design for a bag holding tray, as shown and described.

DESCRIPTION

FIG. 1 is a top-front-left perspective view of a bag holding tray showing my new design;

FIG. 2 is an enlarged view of area 2 encircled in FIG. 1;

FIG. 3 is an enlarged view of area 3 encircled in FIG. 1;

FIG. 4 is a top-rear-right perspective view of the bag holding tray;

FIG. 5 is an enlarged view of area 5 encircled in FIG. 4;

FIG. 6 is an enlarged view of area 6 encircled in FIG. 4;

FIG. 7 is a bottom-front-left perspective view of the bag holding tray;

FIG. 8 is an enlarged view of area 8 encircled in FIG. 7;

FIG. 9 is a bottom-rear-right perspective view of the bag holding tray;

FIG. 10 is an enlarged view of area 10 encircled in FIG. 9;

FIG. 11 is an enlarged view of area 11 encircled in FIG. 9;

FIG. 12 is a top view of the bag holding tray;

FIG. 13 is an enlarged view of area 13 encircled in FIG. 12;

FIG. 14 is a bottom view of the bag holding tray;

FIG. 15 is an enlarged view of area 15 encircled in FIG. 6A;

FIG. 16 is an enlarged view of area 16 encircled in FIG. 14;

FIG. 17 is a front view of the bag holding tray;

FIG. 18 is an enlarged view of area 18 encircled in FIG. 17;

FIG. 19 is a rear view of the bag holding tray;

FIG. 20 is an enlarged view of area 20 encircled in FIG. 19;

FIG. 21 is a left side view of the bag holding tray; and,

FIG. 22 is an enlarged view of area 22 encircled in FIG. 21.

The broken lines in the drawings depict portions of the bag holding tray that form no part of the claimed design.
